(57) **CLAIM**

The ornamental design for a novelty gas pump nozzle, as shown and described.

DESCRIPTION

FIG. 1 is a perspective view of a novelty gas pump nozzle showing the new design;

FIG. 2 is another perspective view thereof, shown broken away for ease of illustration;

FIG. 3 is a right side elevation view thereof, shown broken away for ease of illustration. The left side view is a mirror image of the right side;

FIG. 4 is a front end view thereof, shown broken away for ease of illustration;

FIG. 5 is a back end view thereof, shown broken away for ease of illustration;

FIG. 6 is a top plan view thereof, shown broken away for ease of illustration;

FIG. 7 is a bottom plan view thereof, shown broken away for ease of illustration; and,

FIG. 8 is an environmental view showing the novelty gas pump nozzle in use.

The broken lines shown in FIG. 8 are for environmental purposes only and form no part of the claimed design.
